UNITED STATES PATENT OFFICE.

CHARLES J. ADDY, OF MALDEN, MASSACHUSETTS, ASSIGNOR TO THE TAPLEY MACHINE COMPANY, OF PORTLAND, MAINE.

HEEL-BURNISHING MACHINE.

SPECIFICATION forming part of Letters Patent No. 443,420, dated December 28, 1890.

Application filed September 22, 1890. Serial No. 365,740. (No model.)

To all whom it may concern:

Be it known that I, CHARLES J. ADDY, of Malden, county of Middlesex, State of Massachusetts, have invented an Improvement in Heel-Burnishing Machines, of which the following description, in connection with the accompanying drawings, is a specification, like letters and figures on the drawings representing like parts.

This invention has for its object to improve and simplify the construction of heel-burnishing machines of the class represented in United States Patent No. 318,340, granted to me May 19, 1885.

The improvements made the subject of this patent relate more especially to means for reciprocating the tool-carrying arm longitudinally while it is being vibrated, so as to enable the tool carried by the arm to act upon the heel from its top lift to its seat end. It is well understood that the jack has to be raised and lowered according to the particular part of the heel being acted upon by the tool, so as to reach the breast corners, and I have therefore combined with the device for controlling the backward and forward movement of the tool-carrying arm an arm which raises the jack or permits it to fall, according to the position of the tool upon the heel being burnished.

Figure 1 in side elevation represents a sufficient portion of a heel-burnishing machine to enable my invention to be understood; Fig. 2, a section in the line x , Fig. 1, looking toward the left. Figs. 3 and 4 are details to be referred to.

Referring to the drawings, A represents a column; a , an oscillating shaft therein having upon its end a pinion b , the said shaft having a connected tool-carrying arm c' , provided with a heel-burnishing tool c^2 . This arm c' is normally acted upon by a leaf-spring, (marked c^3 .) The jack to hold the shoe the heel of which is to be burnished is represented as a yoke f^f' , having a shank g , the jack resting between a forked loop s . These parts so far described are substantially the same as in United States Patent No. 318,340, and in practice the shaft a will be oscillated by a lever having segmental teeth at its upper end which

engage the pin b , substantially as in the said patent and as in United States Patent No. 328,371. In this present machine, however, the arm c' is pivoted at 2 upon a counter-weighted block 3, which is feather-keyed upon the shaft a , so as to be slid thereon, as will be described, in order to enable the tool c^2 during its vibrations to travel from the tread end of the heel to the heel-seat end and back again, such motion being depended upon herein, because the jack holding the shoe is jointed or connected by a latch 4 to the column A, so that the jack itself does not have any horizontal movement in the direction of the length of the shaft a . The block 3 is herein represented as provided with a hub 5, having an annular groove in which enters a suitable roller or other stud 6, forming part of a lever or arm 7, pivoted at 8 upon a stud carried by the frame-work. This lever is represented as 70 having three arms, one arm 9 having jointed to it a link 10, connected at its lower end to a treadle 12, normally held up by a spring 13. The depending lower arm 14 of the three-armed lever has a cam bar or finger 15, made 75 cam-shaped at or near its outer end, which arm works against a roller or other stud 16 of the jack.

Referring to Fig. 1, the tool c^2 is shown as resting upon the heel near its tread end, at 80 which time the jack is elevated into its highest position. It will be supposed that the shaft a is being oscillated and that the tool is rubbing the heel from breast corner to breast corner, as usual. Now by putting the foot 85 upon the treadle 12 the three-armed lever referred to will be turned, sliding the block 3 to the left upon the oscillating shaft a , causing the tool to travel from the tread end toward the seat end of the heel, and during this 90 longitudinal movement of the arm c' and tool the projection 15, supporting the jack through the roll 16, will be retracted or moved to the right, bringing the cam-shaped part of the said arm under the roll and letting the jack 95 drop.

This invention is not limited to the exact construction of the arm 15 or to the exact shape of the lever for moving the block 3, as various different shapes of such parts might 100

be employed without departing from my invention.

Fig. 3 shows part of the jack and part of the column with the latch 4.

Referring to Fig. 4, it shows part of the jack, having the roller-stud 16 pivoted in a slot in the same, the arm 15 also entering the said slot below the roller.

I am aware that prior to my invention it has been proposed to mount a shoe in such manner that it might be oscillated under a tool having a movement in the direction of the height of the heel.

I claim—

- 15 1. A heel-burnishing machine containing the following instrumentalities, viz: a substantially-stationary jack to hold the shoe the heel of which is to be burnished, an oscillating burnishing-tool, its carrying-arm, the block 20 upon which the said arm is pivoted, and the oscillating shaft upon which the said block is fitted to slide longitudinally and to oscillate therewith, combined with a lever or arm to engage a part of the said block and move the 25 same longitudinally upon the said shaft during its oscillation, whereby the burnishing-tool during the oscillations of the shaft is

made to travel from the tread end to the heel-seat end of the heel, substantially as described.

2. In a heel-burnishing machine, the following instrumentalities, viz: an oscillating shaft, a block splined thereon and made longitudinally movable with relation to the said shaft, a tool-carrying arm c' , carried by the 35 said block and provided with an arm or projection 15, having a cam-surface, connections to move the said arm or projection, and a jack restrained from vibration in the direction of the length of the said oscillating shaft and 40 having a roller or other stud, the parts being united to operate substantially as described, whereby as the burnishing-tool is made to travel from the tread end of the heel to the seat end, and vice versa, the jack is lowered 45 and raised as required, substantially as described.

In testimony whereof I have signed my name to this specification in the presence of two subscribing witnesses.

CHARLES J. ADDY.
